UNITED STATES PATENT OFFICE.

CHARLES H. CLARK, OF CRAFTON, PENNSYLVANIA, ASSIGNOR TO CLARK CAR COMPANY, OF PITTSBURGH, PENNSYLVANIA, A CORPORATION OF NEW JERSEY.

ТИЛТИНГ СІД-ДАМП САР.

1,007,533.

Specification of Letters Patent. Patented Oct. 31, 1911.

Application filed June 24, 1909. Serial No. 504,046.

To all whom it may concern:

Be it known that I, CHARLES H. CLARK, a resident of Crafton, in the county of Allegheny and State of Pennsylvania, have invented certain new and useful Improvements in Tilting Side-Dump Cars, of which the following is a specification.

This invention relates to that class of dump cars in which the car body is inclined for discharging the load, and it contemplates a rocker mounting for the body of improved construction, the arrangement being such that during the tilting movement of the body the center of gravity of the combined body and load lowers, while the center of gravity of the body alone rises, with the result that the movement to inclined position is facilitated, and after the load has been discharged the tendency of the raised center of gravity of the body to lower causes the body to move with ease back to normal position and remain therein.

A further purpose is to provide improved means for controlling and limiting the tilting movement.

A further characteristic of the invention is the arrangement of the side walls of the car body, with means operating automatically to open the wall outwardly and downwardly at the emptying side of the car. A further characteristic of the automatically opening side wall is that it forms a chute-like extension which directs the outflowing material farther away from the track than if it were to fall directly from the inclined bottom of the car.

Still a further object is to provide improved cylinder and piston means for rocking the car body, together with improved detachable connections between the body and the pistons, whereby either of the cylinders may be rendered inoperative while the body is being rocked by the other cylinder.

The invention also includes features of novelty in the construction of the under-frame, and in the rocker bolsters which support the body.

In the accompanying drawings, Figure 1 illustrates the improved car, one-half thereof being shown in side elevation and the other half in vertical section. In Fig. 2 one-half of the car is shown in top plan, and the other half on a plane beneath the rocking car body. In Fig. 3, one-half of the car is shown in end elevation and the other half in sectional elevation at the bolster.

Fig. 4 is a sectional elevation taken on line 4-4 of Fig. 1, the body being shown in normal position in full lines and tilted, as when dumping, in dotted lines.

60

Referring to the drawings, the under-frame consists of the central longitudinal girders 2 through which the draft forces are transmitted, and the bolsters 3 connecting the girders 2 coincident with center bearings 4. Girders 2 are covered for a portion of their length by plates 5. Mounted on each of bolsters 3 is the transverse horizontal rack 6, and operative thereon is the toothed rocker 7 of the body bolster 8.

70

As here constructed, the car body, carried by bolsters 8, consists of the longitudinal center and side floor girders 9 and 10, 11 being the floor or bottom, 12 the end walls, and 13 longitudinal side walls. Trunnions 14 are projected from end walls 12 at the center about which the body turns when tipping, the trunnions moving in a horizontal line during such movement beneath the flanged or overhanging upper end 15 of the yoke-like frames 16 raised from the ends of the car underframe. These frames 16 provide stops for the trunnions when the body reaches the limit of its tilting movement and prevent the same from becoming displaced.

75

The body is rocked by means of two cylinders 17 suspended on opposite sides of girders 2 by hangers 18, the cylinders being tied together by bars 19. The piston rod 20 of each cylinder carries at its upper end the horizontally turning clevis 21, the upwardly disposed arms of which are formed with the reversely facing hooks 22 adapted, when the clevis is turned, to engage or disengage bolt 23 at the lower end of the straps 24, depending from the under side of the body. Clevis 21 may be provided with a pivoted handle or arm 24' which may be turned upward from the position indicated 100 in Fig. 4 for turning the clevis as required.

95

Cylinders 17 are connected to and operated by compressed air secured from the air-brake equipment or otherwise, but such connections are not shown as they are old in the art, and no novelty is claimed for them.

105

The body is tilted or rocked by operating the cylinder on the side upon which the body is to lower, the air under pressure being admitted to the upper end of the cylinder, with the lower end of the latter open to an exhaust, as will be understood. But before

thus operating the cylinder, the connection between the car body and the piston rod of the other cylinder is broken, as at the right hand of Fig. 4, clevis 21 being turned to disengage hooks 22 from bolt 23, so that straps 24 may rise free thereof, as in dotted lines in said figure.

At the base of each of the swinging side walls 13 are the inward horizontal arms 25 which are hinged at 25' beneath the floor of the body, and coincident with these hinged arms are like downwardly extending arms 26. The latter are connected by links 27 to the extremities of the transverse floating beam or bar 28. As many of these connections between the opposite walls may be provided as required, four being here shown. Each of bars 28 operates between the slightly separated portions of a cradle-like bracket 29 supported by girders 2. The cradles have their inner faces or edges 30 curved downwardly to a central point, and adapted to travel on these curved faces are rollers 31 on opposite sides at the center of bar 28. Said bar rests on rollers 32 at the base of the cradle and is always in engagement with at least one of these rollers. When the car body begins to tip, for instance as in Fig. 4 with the left-hand side lowering, such movement, irrespective of pressure on side wall 13, imparts longitudinal movement to bar 28 toward the opposite side of the car, and at the same time causes roller 31 to ride upwardly on the curved face 30 of cradle 29, as in dotted lines in Fig. 4, this movement swinging side wall 13 outward and downward, at the same time holding wall 13 on the opposite side in upright or closed position. When fully tipped, the body and its open side wall are in the position indicated in dotted lines of Fig. 4, at which time the open and extended wall forms a chute-like extension for diverting the emptying load away from the track.

It is characteristic of the invention that the center of gravity of the loaded body lowers during the tilting movement, thereby facilitating the dumping operation. At the same time the center of gravity of the car body itself rises, so that when entirely empty its tendency is to rock back to upright or horizontal position and to remain in that position.

A further feature of the invention is the swinging steps 33 at the car ends, and each connected by a link 34 to end frame 16, so that as the car rocks to tilting position the steps on the emptying side are drawn inward and out of the way.

60 I claim:—

1. The combination of a car body adapted to tip toward either side for dumping, doors for opposite sides of the body, operating means common to the opposite doors holding them closed when the body is in upright

position, and means actuating the operating means to open and close the door at the dumping side of the car as said side lowers and rises.

2. The combination of a car body adapted to tip toward either side for dumping, doors for opposite sides of the body movable therewith, movable means connecting the opposite doors, and fixed means co-operating with the movable means during the tipping movement of the body for positively opening the door at the dumping side of the car during its downward movement and for positively closing the door during the upward movement of said car side.

3. The combination of a car body adapted to tip toward either side for dumping, outwardly and downwardly swinging doors mounted on the body at opposite sides thereof, operating means common to the opposite doors holding them closed when the body is in upright position, and means actuating the operating means to open and close one door during the tipping movement and at the same time hold the other door closed.

4. The combination of a car body adapted to tip toward either side for dumping, outwardly and downwardly swinging doors mounted on the body at opposite sides thereof, operating means beneath the body and connected to both doors and holding them closed when the body is in upright position, and means actuating the operating means to positively open and positively close one door during the tipping movement and at the same time hold the other door closed.

5. The combination of a car underframe, a body, doors for opposite sides of the body, rockers tiltably supporting the body, devices secured to the body at the center of rocking, means fixed to the frame and engaged by said devices for limiting the tilting movement, movable means beneath the body operatively connecting its opposite doors, and means fixed to the underframe and co-operating with the door connecting means during the tilting movement for opening the door at the lowering side of the car.

6. The combination of a tilting car body with means for inclining the same toward either side of the car, doors for the opposite sides of the body, a movable member extending transversely of the car and operatively connected to the doors, and fixed guiding means directing the movement of said member when the body tilts, the connecting member operating the door at the lowering side of the body.

7. The combination of a tilting car body with means for inclining the same toward either side of the car, doors for the opposite sides of the body, a movable member beneath and extending transversely of the body and operatively connected to the opposite doors, and fixed guides meeting at the cen-

- ter of the car and diverging upwardly in direction transversely of the car for directing the movement of said transverse member as the body tilts.
- 5 8. The combination of a car underframe, a body, doors for opposite sides of the body, rockers tiltably supporting the body, a movable member extending transversely of the body and operatively connected to the opposite doors, and guide means fixed to the underframe for directing the movement of said transverse member as the body tilts.
- 10 9. The combination of a car underframe, a body, doors for opposite sides of the body, rockers tiltably supporting the body, a movable member extending transversely of the body and operatively connected to the opposite doors, guides secured to the underframe and meeting at the center of the car 20 and diverging upwardly in direction transversely of the car, and rollers on the transverse member movable on said guides.
- 15 10. A tilting car body, means for inclining the same toward either side of the car, side walls for the body movable therewith and mounted to open outwardly, and means connecting the side walls and operating during the tilting movement to open the side carried by the lowering portion of the body.
- 25 11. A tilting car body, means for inclining the same toward either side of the car, side walls for the body mounted to open outwardly and downwardly, a transverse member beneath the body and connected to each 30 of the side walls, and means for controlling the movement of the transverse member during the tilting movement of the body.
- 35 12. A tilting car body, means for inclining the same toward either side of the car, side walls for the body hinged to swing downwardly and outwardly, downward extensions on the doors, a transverse bar, and links connecting the ends of the bar to said 40 downward extensions.
- 45 13. A tilting car body, means for inclining the same toward either side of the car, side walls for the body hinged beneath the latter to swing outwardly and downwardly, downward extensions on the doors projecting beneath the plane of the hinges, a transverse bar and links connecting the opposite 50 ends thereof to the downward wall extension, and curved guides engaged by the bar for limiting and directing the movement thereof during the tilting movement of the body.
- 55 14. The combination of a car body, rockers supporting the body and adapted to incline the same toward either side of the car, and power cylinders at opposite sides of the car center with their pistons separately 60 detachably connected to the car body.
15. The combination of a car body, rockers supporting the body and adapted to incline the same toward either side of the car, 65 the rockers disposed transversely of the car and normally supporting the body centrally thereof, power cylinders on the car at opposite sides of the center, pistons for the cylinders, and separate detachable connections 70 between the pistons and the body at opposite sides of the center of the latter.
16. The combination of a car body, rockers supporting the same and adapted to incline the body for dumping at either side, 75 side walls for the body hinged to swing outwardly and downwardly, power cylinders on the car beneath the body with their pistons connected to the body at opposite sides of its center, a transverse bar beneath the 80 body, links connecting the ends of the bar to the lower portions of the side walls, and upwardly extending oppositely curved brackets engaged by the bar for limiting and directing its movement during the tilting of the body.
17. The combination of a car underframe, transverse racks secured thereto, a car body, rockers at the under side thereof engaging the racks on the frame, and power cylinders 90 carried by the frame and having their pistons separately detachably connected to the body.
18. The combination of a car underframe, transverse racks secured thereto, a car body, 95 rockers on the body and engaging the racks on the frame, means controlling the tilting movement of the body, side walls for the body movable therewith and mounted to open downwardly and outwardly, a transverse bar beneath the body, links connecting the ends thereof to the lower portions of the side walls, upwardly extending oppositely curved guides secured to the car frame, and rollers on said bar which move over said 100 guides for limiting and directing the movement of the bar during the tilting of the car body.
19. The combination of a car underframe, a body mounted to tilt thereon, a step pivoted to and depending from the body, and a connection between the step and the underframe operating to draw the step inward as the portion of the car carrying it lowers during the tilting movement.
20. The combination of a tilting car body, a movable step, and means actuated by the movement of the body for moving the step.
